PEDRO VERA, OF BOGOTA, UNITED STATES OF COLOMBIA.

Letters Patent No. 86,046, dated January 19, 1869.

IMPROVED APPARATUS FOR GENERATING HEAT BY FRICTION.

The Schedule referred to in these Letters Patent and making part of the same.

To all whom it may concern:

Be it known that I, PEDRO VERA, of Bogota, in the United States of Colombia, have invented a new and useful Improvement in Generating Heat by Friction; and I do hereby declare that the following is a full, clear, and exact description thereof, which will enable others skilled in the art to make and use the same, reference being had to the accompanying drawings, forming part of this specification.

This invention relates to certain improvements in that class of machines designed to generate heat by friction, for the purpose of generating steam, or warming apartments, &c.; and

It consists in the particular construction and arrangement of parts hereinafter described.

In the accompanying plate of drawings.

Figure 1 represents a longitudinal section of the machine, through the line *x x* of fig. 2.

Figure 2 is an end view of the same, with the cap off (or looking from the line *y y*.)

Figure 3 is a side view of one of the revolving disks.

Figure 4 is a side view of one of the stationary diaphragms.

Similar letters of reference indicate corresponding parts.

The revolving disks and stationary diaphragms are placed in four columns, and supported on shafts and rods, by the ends of the casing. In this example of my invention, four of these columns are shown, but more or less may be employed, as may be desired.

A represents the shell or casing, which is designed to be water and steam-tight, and of sufficient strength to withstand as much pressure as an ordinary steam-boiler.

B represents the disks, which are keyed on to the shafts C.

D represents the diaphragms, which are supported by the rods E, four in number.

The disks B and diaphragms D are each formed with

plain parallel sides, in order that the amount of frictional surface may be as large as possible.

F represents springs, connected, as shown, with each column or series, the pressure of which springs is designed to increase or diminish the friction, by pressing against the revolving disk.

G is a central driving-gear wheel, which is placed upon the independent shaft H, to which motion is imparted by a belt on the pulley I.

J represents pinion-wheels on each of the shafts C, with which the gear-wheel G engages, as seen in the drawing.

K is the cap, by which all the shafts are supported outside the gearing. The cap itself is supported from the end of the shell by plates, as seen at *m m*.

The shafts C pass through stuffing-boxes, where they enter the shell, as seen at *n n* in fig. 1.

The machine being thus constructed, is placed in a horizontal position, (it may be used in any other desired position,) and filled or partially filled with water, when power is applied, and motion is imparted to the disks B, which are revolved with any desired velocity.

The amount of heat generated, will of course depend upon the friction between the disks and the diaphragms, and the velocity of the motion.

I am aware of the patent granted to John W. Cochran, November 19, 1834, for a "furnace for generating heat by friction," but I claim nothing therein shown or described; but

What I claim as new, and desire to secure by Letters Patent, is—

The device for generating heat by friction, when constructed, arranged, and operating as herein described.

The above specification of my invention signed by me, at Bogota, the 13th day of September, 1868.

PEDRO VERA.
